UNITED STATES PATENT OFFICE

ALEXANDER MEISSNER AND OTTO VON BRONK, OF BERLIN, GERMANY, ASSIGNORS TO
GESELLSCHAFT FÜR DRAHTLOSE TELEGRAPHIE M. B. H. HALLESCHES, OF BERLIN,
GERMANY, A CORPORATION OF GERMANY

INDICATOR

Application filed August 19, 1927, Serial No. 214,098, and in Germany August 21, 1926.

This invention relates to a device for indicating alternating potentials.

Arrangements for the indication of alternating potentials, especially high frequency oscillations are known in which a quartz crystal is confined within an exhausted vessel filled with gas so that the potentials set up at the quartz body cause the tube to luminesce. This device involves the great drawback that, on the one hand, it gives rise to very small luminous energy, inasmuch as the potentials across the quartz crystal in the low vacuum are very small. On the other hand, difficulties arise insofar as it is necessary to remove the crystal from the vacuous space and to remount and reseal it therein after grinding away portions thereof whenever it is desired to change the wave of the crystal, in other words, whenever the indicator is to be adapted so as to respond to another wavelength.

The present invention avoids these drawbacks and thus discloses essential technical progress. This progress is attained in that the crystal influenced by the alternating current to be observed, as soon as it happens to be in resonance with the frequency to be influenced, is electrically connected with a luminous or glow-discharge tube located outside the crystal in such a way that the energy of the oscillating crystal excites said luminous tube at the instant when resonance arises. This excitation may be further intensified by applying an auxiliary (biasing) potential across the terminals of the luminous tube whereby the breakdown (striking) potential of the tube is lowered.

Embodiments of the basic idea of our invention are shown by way of example in the accompanying drawings wherein

Fig. 1 shows one form of our invention and

Fig. 2 shows a modified form of our invention utilizing an exciting battery for a glow discharge tube.

In Fig. 1 Q is a piezo-electric body, say, a quartz crystal, and L a coil which serves for establishing a coupling with the transmitter to be checked. In series with the crystal is arranged a glow-discharge or a helium tube G. By the excitation by the transmitter, the

quartz crystal will be caused to oscillate, energy being given off by the crystal at the instant it starts to oscillate, to the luminous system coupled therewith, the latter being caused to flash up at the instant the quartz crystal happens to be in resonance. 55

In Fig. 2 we have shown an embodiment of our invention wherein the glow tube G is kept in a critical condition by means of battery H. 60

Of course, care must be taken in this arrangement so that the flashing up of the luminous tube will not be caused by the direct energy of the oscillation to be controlled, but only by the energy of the quartz crystal itself. The coupling between the quartz crystal and the luminous tube may be inductive, capacitive or galvanic. 65

We claim as our invention:

1. In combination, a glow discharge device, a source of potential for keeping said device in a critical condition, a piezo electric crystal and an inductor in series with said glow discharge device, and means for supplying an alternating potential to said inductor. 70

2. In combination, a piezo electric crystal, a glow discharge device and an impedance in series; a source of potential shunted across said glow discharge device and means for supplying an alternating potential to said impedance whereby when said potential corresponds in frequency to that of the crystal, a discharge occurs across said glow discharge device. 75
